UNITED STATES PATENT OFFICE.

ISIDOR KITSEE, OF PHILADELPHIA, PENNSYLVANIA.

TELEPHONY.

No. 844,811.

Specification of Letters Patent.

Patented Feb. 19, 1907.

Application filed October 14, 1905. Serial No. 282,817.

To all whom it may concern:

Be it known that I, ISIDOR KITSEE, of the city and county of Philadelphia and State of Pennsylvania, have invented certain new and useful Improvements in Telephony, of which the following is a specification.

My invention relates to an improvement in telephony, and has more special reference to telephonic lines wherein two or more ¹⁰ stations are connected in multiple arc. In such a system it often occurs that the subscriber has to remove his receiver from the hook to call up the operator in charge for the purpose of communicating with another ¹⁵ subscriber only to find out that his own line is busy on account of the other party connected thereto using the line. A device, therefore, automatically indicating the condition of such line, if the same is busy or not, ²⁰ would be of great advantage.

My invention, therefore, has for its object to provide such an automatic device to notify the subscriber if his circuit is free or busy.

The accompanying drawing illustrates in ²⁵ diagrammatic view a telephonic line with three substations connected thereto each provided with such means.

1 and 2 are the main lines; *a* and *b*, the lines connecting the apparatus of the different stations; *c*, the microphonic transmitter; *d* and *e*, the two coils of an inductorium; *h*, a contact-point adapted to contact with the lever *g* when relieved of the receiver *f*. Thus far the arrangements and devices are the ³⁵ same as are usually employed, but the ringer or bell is omitted, as the connection of the same differs in the various systems of to-day.

The automatic device for indicating the condition of the line is illustrated as ⁴⁰ embracing the wire *k*, connected to the contact *h* at one terminal and the electromagnet *m* at the other terminal. The other terminal of the electromagnet *m* is connected through the wire *l* with the lever *g*. In proximity to ⁴⁵ this electromagnet is the lever-armature *m'*, held away from the electromagnet by the spring *m²* and carrying the shield *m³*. The movement of this armature is limited by the stops *s* and *s'*, respectively. In proximity to ⁵⁰ the shield are the two designations—such, for instance, as the words "Busy" and "Free"—placed in such a manner that the shield when covering the one exposes the other, and vice versa.

⁵⁵ The coil of the electromagnet *m* should be of a very high resistance. In fact, it is pref-

erable in a telephonic system wherein twenty-four volts are employed to make this resistance of a value ranging from twenty-five thousand to fifty thousand ohms. The ⁶⁰ latter figure is even preferred to the former; this for the twofold reason that the amount of current flowing in this circuit should not be sufficient to actuate any of the low-wound electromagnets located at the central station, and for the second reason that the least amount of current should be wasted in such circuit, for, as it is clearly illustrated in the drawing, the circuit for each of the substations *A A A* is completed as far as conductivity is concerned through this high-resistance electromagnet. ⁷⁰

In a twenty-four volt system with, say, four subscribers on the line, and a fifty-thousand-ohm coil for each subscriber, only about ⁷⁵ one-half of a mill-ampere is used up by each subscriber's circuit, which would make in a year less than five amperes, or less than one hundred and twenty watts per subscriber, which would be, figuring on the average cost ⁸⁰ of electric energy, less than five cents for all four subscribers on the line per year; but it is obvious that the resistance of these coils may differ according to requirements, and accordingly more or less current will flow through ⁸⁵ the circuit.

The operation of this circuit and device attached thereto is as follows: Normally—that is, when the receiver is on the hook—the lever is out of electrical connection with the contact *h* and the circuit is established embracing wire *l*, wire *a*, microphonic transmitter *c*, coil *d*, wire *k*, coil of electromagnet *m*, wire *l*, wire *b*, and main line 2. In this condition the electromagnet *m* is energized, ⁹⁰ drawing the armature *m'* with its appended shield *m³* toward the stop *s*, whereby the designation "Free" is exposed, and as the current divides in accordance with the resistance and each of the substations is of ⁹⁵ about the same resistance in each of the substations will the designation "Free" be exposed. When, now, one of the subscribers removes his receiver from the hook, the lever *g* will come in electrical connection with ¹⁰⁰ the contact *h*, thereby shunting its own electromagnet *m*. The armature released from its magnetic pull will be drawn by the spring *m²* in contact with the stop *s'*, whereby the designation "Free" will be covered by the ¹⁰⁵ shield *m³* and the designation "Busy" will be exposed, and, as according to the above-cited

rule the current will seek the path of least resistance, most all of the current through the main wires 1 and 2 will pass through the station having the receiver off the hook, and 5 none, or only an insufficient current, will pass through the electromagnets m of the other stations, and the armature m' of each of said stations also released from their magnetic pull will be drawn by the spring m^2 10 away from the electromagnet m and in contact with the stop s' , thereby covering in each station the designation "Free" and exposing at each station the designation "Busy," thereby notifying each of the sub- 15 scribes connected to this line the condition of the wire.

It is obvious that the device may be placed on the portable or stationary phone or may be secured at any desired point separate therefrom.

If it is desired, the electromagnet m may also be used for "ringing-up" purposes. In this case the usual bell and clapper has to be

added; but I do not deem it necessary to illustrate this arrangement here, as the use of 25 bells and clappers are well understood and may differ according to requirements.

Having now described my invention, what I claim as new, and desire to secure by Letters Patent, is—

30 A telephonic line having a series of substations connected thereto in multiple arc, an electromagnetic resistance in series with the circuit of each of said stations, means to short-circuit said resistance by the removal 35 of the receiver from its hook, an armature for each of said electromagnetic resistances, and a signal in operative relation to said armature.

In testimony whereof I affix my signature 40 in presence of two witnesses.
